Inventor

Paul L. Schluttig

UNITED STATES PATENT OFFICE

166,827

MELTING POT FOR COSMETIC POMADE

Pearl L. Schluttig, Washington, D. C.

Application September 25, 1951, Serial No. 16,738

Term of patent 14 years

(Cl. D81--1)

To all whom it may concern:

Be it known that I, Pearl L. Schluttig, a citizen of the United States, residing at Washington, in the District of Columbia, have invented a new, original, and ornamental Design for a Melting Pot for Cosmetic Pomade, of which the following is a specification, reference being had to the accompanying drawing, forming a part thereof.

Fig. 1 is a perspective view of a melting pot for cosmetic pomade showing my new design;

Fig. 2 is a top plan view thereof;

Fig. 3 is a top plan view of the lower half with the top removed;

Fig. 4 is a vertical section on line 4—4 of Fig. 2.
I claim:

The ornamental design for a melting pot for cosmetic pomade, as shown.

PEARL L. SCHLUTTIG.
